UNITED STATES PATENT OFFICE.

EDWARD O. KEATOR, OF CINCINNATI, OHIO.

COMBINED WIRE STRETCHING AND SPLICING AND DRILLING MACHINE.

1,332,988.

Specification of Letters Patent.

Patented Mar. 9, 1920.

Application filed April 4, 1917. Serial No. 159,601.

To all whom it may concern:

Be it known that I, EDWARD O. KEATOR, a citizen of the United States of America, and resident of Cincinnati, in the county of 5 Hamilton and State of Ohio, have invented a new and useful Improvement in Combined Wire Stretching and Splicing and Drilling Machines, of which the following is a specification.

10 An object of my invention is to produce a portable wire stretching and splicing and drilling machine.

15 A further object is to produce a wire stretching and splicing and drilling machine for use by concrete contractors in the erecting of forms, by farmers in the building of wire fences, the baling of hay and other purposes, by box makers in the manufacture of wire bound boxes, by line men in 20 the construction of telephone and telegraph wires, and by others who have occasion to handle wire.

25 These and other objects are attained in the wire stretching and splicing machine described in the following specification and illustrated in the accompanying drawings, in which:

30 Figure 1 is a side elevation of my improved machine with wires which have been stretched and spliced, in position therein.

Fig. 2 is a side elevation of the machine disclosed in Fig. 1 and looking in the direction indicated by the arrow A disclosed in Fig. 1.

35 Fig. 3 is an elevation of my improved machine, taken from the opposite side disclosed in Fig. 2, the machine being shown in use as a power feed drilling machine.

40 Fig. 4 is a transverse sectional perspective view taken on the line 4—4 of Fig. 1.

Fig. 5 is a perspective view of a winding crank adapted to operate my improved machine.

45 Figs. 6 to 9 inclusive, are views of various wire splices accomplished by the use of my improved machine.

50 My improved machine consists of a frame 5 having bearings, 6, 7, 8 and 9 adapted to journal the hollow longitudinally extending shaft 10 of a bevel gear 11 which is coaxial with the axis of frame 5. Extending at right angles to the axis of frame 5 are bearings 12 and 13 adapted to journal the transversely extending shaft 14 of a bevel gear 15

which meshes with bevel gear 11. Shaft 14 55 of bevel gear 15 is provided with a keyway 16 adapted to receive a key 17 of a winding crank 18, see Fig. 5, which is provided for operating the gears. Adjacent to bearings 12 and 13, additional bearings 19 and 20 are 60 formed in the frame 5, these bearings being adapted to journal transversely extending shaft 21. Shaft 21 is provided with a keyway 22 for receiving the key 17 of winding crank 18. The inner end of shaft 21 is provided with an enlargement 23 having a diametrically extending slot 24 adapted to receive the wire to be tightened or stretched. Shaft 10 is provided with a longitudinally extending slot 25 which communicates with 70 the hollow interior of the shaft. Located in alignment with the axis of shaft 10 and adapted to register with its hollow interior, is a lug 26 having a groove 27 adapted to receive the wire extending through shaft 10. 75 In the end of this lug two rollers 28 and 29 are mounted, the end of the lug being provided with a V-shaped notch 30 for a purpose hereinafter to be described. On one side of the lug a set screw 31 is provided, 80 the set screw being adapted to be brought to close the slot 27 to prevent the wires which have been brought into engagement therewith, from being displaced therefrom. Adjacent to this set screw 31 and located 85 toward gear 11, but entering lug 26 from the opposite side, is another set screw 32. This set screw is so positioned as to intercept the axis of the frame and consequently to engage the wire or wires occupying the slot 27. 90 In that end of shaft 10 adjacent to lug 26, a set screw 33 is provided. This set screw is adapted to move transversely of the slot 25 and to be brought into engagement with the wire or wires occupying the slot. Adjacent to the opposite end of shaft 10, and in bearing lug 9, a slot 34 is provided a set screw 35 being located adjacent to bearing 9 for the purpose of intercepting the slot to engage a wire located therein. Extending 95 from bearing lug 9 is the rib 36 on which bearing 19 of shaft 21 is formed. This rib carries a pivotally mounted pawl 37 which is adapted to engage a ratchet 38 secured to shaft 21. Adjacent to pawl 37 and formed 100 as an integral part of rib 36 is a lug 39 carrying a set screw 40 which is adapted to clasp a wire passing through the machine. 105

Located adjacent to lug 39 and formed as an integral part of the rib 41 on which bearings 13 and 20 are provided, is a handle 42 by means of which the machine is held in 5 position.

Pivotaly mounted on gear 11 and adapted to engage slot 25 formed in shaft 10 thereof, is a finger 43, see Fig. 4, having its end 44 adapted to pass through the slot and 10 to engage an opening 45 on the opposite side of the shaft. The formation and position of this finger is more clearly disclosed in Fig. 4. Formed on the frame 5 and extending from opposite sides thereof, are 15 brackets 46 and 47 adapted to journal the respective rollers 48 and 49. In shaft 21 between ribs 36 and 41, are formed a series of transversely extending apertures 50 adapted to receive a small hand pin for a purpose 20 hereinafter to be more fully set forth.

In operation;

It will be assumed that it is desired to stretch and to splice two pieces of wire 51 and 52, such as disclosed in Figs. 1, 2 and 25 4. To perform this operation, the end of wire 51 is passed through the machine by passing it through lug 39, to one side of enlargement 23 of shaft 21, through slot 34 of bearing 9, through slot 25 of shaft 10, 30 and through slot 27 of lug 26. The opposite wire 52 is passed from the opposite direction through lug 26, through shaft 10, through bearing 9, and its end is brought into engagement with slot 24 of enlargement 35 23 of shaft 21. Set screw 40 is then tightened up on wire 51. The winding crank 18 is then placed upon shaft 21 and the shaft is rotated in such a direction as to wind wire 52 upon its enlargement 23 as disclosed 40 in Fig. 1, pawl 37 in coöperation with ratchet 38, preventing unwinding movement of the wire. By the winding operation of shaft 21, the two wires are stretched or tightened to the required amount. Set screw 32 is brought into engagement with 45 the wires in slot 27. Finger 43 is then brought so that its end 44 passes between the wires and into engagement with aperture 45 of shaft 10, as disclosed in Fig. 4. The winding crank is then removed from the shaft 21 and placed upon shaft 14. Shaft 14 is then rotated to cause shaft 10, through the gears 11 and 15, to rotate. This results in the wires being twisted in the manner 50 illustrated in Fig. 6. The machine is now removed from the tightened and spliced wires by loosening set screws 40, and 32, key 43 being removed from between the wires and twisted portion 53 of wire 52, being 55 slipped from enlargement 23. The machine now being free it may be lifted from the wires and the wires trimmed by cutting off twisted end 53, straight end 54 of wire 51, and if desired, one side of the loop 60 formed by key 43, may be cut to prevent 65

the wires untwisting. This leaves the stretched and spliced wires in the condition disclosed in Fig. 6.

Should it be desired merely to splice the wires without stretching them, either a short 70 or long splice may be made. To make the short splice, one wire is passed through the machine from one end until it passes set screws 32 and 33, the opposite wire being passed through the opposite end of the machine and beyond set screws 32 and 33. These set screws are then tightened against the two wires to clamp them firmly in position. Winding crank 18 is placed on shaft 14 and shaft 10 is rotated, thus causing the 80 two wires to be twisted together between set screws 32 and 33 to produce the result disclosed in Fig. 7.

Should it be desired to produce a long 85 splice the same operation is performed, except that set screw 35 is utilized as the stationary set screw in place of set screw 32, set screw 33 again being employed as the rotating set screw. The distance between set screws 33 and 35 being greater than between 90 set screws 32 and 33 the splice produced is like that disclosed in Fig. 8.

In using my improved machine for the purpose of wiring boxes, the notch 30 is brought into engagement with the corner 95 of the box and the two ends of the wire passing around the box, are passed through the machine and beneath set screw 33. In this position, the set screw is brought into clamping engagement with the ends of the 100 wire and shaft 14 is rotated to cause shaft 10 to twist the ends between its set screw 33 and the box, the wire passing beneath rollers 28 and 29. This produces the result disclosed in Fig. 9. After the ends have 105 been trimmed, the twisted wires are bent down into engagement with the sides of the box. For the purpose of rendering my improved machine easier to operate, especially when particularly stiff wire of large 110 diameter is to be handled, I have devised the extension crank, disclosed in Fig. 5, which is composed of two sections 55 and 56. Section 55 carries the handle 57 and section 56 carries the boss 58 adapted to receive the 115 shafts 14 and 21. Any suitable means such as screws 59 and 60 may be provided for securing the sections 55 and 56 in their adjusted positions to render the crank longer or shorter, as desired.

Should a loose and sagging wire be required to be tightened, as is frequently found in fences and the like, the machine is placed upon the wire by bringing its slots 120 27, 25 and 34 into engagement with the wire 125 and by placing the wire within slot 24 of the wire tightening device. The winding crank is then placed upon shaft 21 and the shaft is rotated so that the wire is wound upon enlargement 23 of the wire tightening 130

mechanism. This operation brings that portion of the wire which passes lug 39, into such a position that it will enter the slot formed therein. The wire having been stretched, set screws 40 and 32 are tightened. The wound up wire is then removed from enlargement 23 and is straightened out, it being severed at the point where it extends beyond slot 34 of bearing lug 9. The straightened out end of the wire is then laid within the slots 34, 25, 27 and set screws 35 and 33 are brought into clamping engagement with the parallel ends of the wire. Winding crank 18 is then removed from shaft 21 and placed upon shaft 14, shaft 10 then being rotated because of its connection with shaft 14 through gears 11 and 15. This results in the wires between set screws 33 and 35 being twisted to produce a long splice. The machine may then be removed by releasing set screws 40, 35, 33 and 32, the extending untwisted ends of the wire then being cut off.

A further use to which my improved wire stretching and splicing machine may be placed, is to stretch wires extending between opposite mold members for the purpose of bringing the mold members into proper position to produce a mold of the required size. This is accomplished by placing the wire which extends through the mold members, through slot 27 and into position to be clamped by set screw 32. A lug 26^a, which extends from lug 26, is then employed as a fulcrum about which the machine may be rocked to bring tension to bear upon the wire clamped by set screw 32 and passing through the mold members. After the wire has been stretched, the usual clamp may be placed thereon to hold the mold members in position.

An additional feature of my improved machine is that I have provided a hook 42 upon handle 42 of my machine, so that the machine may be conveniently hung upon wires or other objects when it would be inconvenient to find a place to lay it.

I have so constructed my improved wire stretching and splicing machine, that it may readily be used as a power feed hand drill, the same instrumentalities as are employed for handling wire, being employed when the machine is in use as a drill. This particular use of my improved machine is fully disclosed in Fig. 3. A drill bit of the size of the bore to be made, is placed in position

within slot 27 of the machine and passed into the hollow of shaft 10. Set screw 33 is then brought into engagement with the drill to hold it tightly. By applying the crank to shaft 14 the shaft may be rotated and thus caused to operate the drill. However, when it is desired to use the machine as a drill embodying power feeding mechanism, I place a wire 62 around the object 63 to be drilled, passing the ends of the wire over the pulleys 48 and 49 and bringing the ends into engagement with slot 24 of enlargement 23 of shaft 21. Crank 18 is then placed on shaft 21 to rotate it and to tighten the wire. Ratchet 38 and pawl 37 coact to retain the wire in its tightened condition and thus place a certain amount of pressure upon the drill 61. By placing crank 18 upon shaft 14, the drill is then rotated until it has entered piece 63 to the point where the tension on wire 62 no longer exerts any force upon it. The crank is then removed and placed upon shaft 21 again to tighten the wire. In this manner the drill may be caused to bear tightly against the work to be drilled and thus to work its way under power through the piece. If desired, the crank may be left on shaft 14 and a short rod may be passed through any one of the apertures 50 in position to be grasped by the hand of the operator as he takes hold of the handle 42, thus enabling him to maintain a substantially uniform tension on the wire during operation of rotating the drill.

What I claim is:

A wire splicing machine comprising a frame, a longitudinal shaft journaled in the frame and having a longitudinal wire receiving groove, a transverse shaft mounted in the frame at one end of the longitudinal shaft and having a wire receiving groove in it, a stationary lug at the opposite end of the longitudinal shaft, and having a longitudinal groove in alignment with the groove in the longitudinal shaft, a second lug upon the opposite side of the frame from the first lug, a clamp for securing a wire upon each lug, and means for rotating the shafts.

In testimony whereof, I have hereunto subscribed my name this 26th day of March, 1917.

EDWARD O. KEATOR.
